(No Model.)

J. SACHS.

AUXILIARY FIRE ALARM TELEGRAPH SYSTEM.

No. 515,503.

Patented Feb. 27, 1894.

UNITED STATES PATENT OFFICE.

JOSEPH SACHS, OF NEW YORK, N. Y.

AUXILIARY FIRE-ALARM-TELEGRAPH SYSTEM.

SPECIFICATION forming part of Letters Patent No. 515,503, dated February 27, 1894.

Application filed February 15, 1893. Serial No. 462,403. (No model.)

To all whom it may concern:

Be it known that I, JOSEPH SACHS, residing in the city of New York, county and State of New York, have invented an Improved Auxiliary Fire-Alarm-Telegraph System, of which the following is a specification.

The present invention relates to auxiliary fire alarm telegraph systems, that is, systems in which one or more fire alarm or similar boxes can be operated from distant points by means of one or more local circuits known as auxiliary circuits. Heretofore the auxiliary circuits have led directly to one of the "street boxes" of the fire alarm circuit; said box containing electric devices whereby the street box could be caused to send in a signal in the same manner as though it were pulled by hand. One such system is described in my Patent No. 481,590, dated August 30, 1892.

According to the present invention the auxiliary circuit does not lead directly to a street box of the fire alarm system, but to an "auxiliary street box" connected in the same fire telegraph or main circuit as the street box, and adapted to send a corresponding signal.

In the drawing the figure is a front view of street and auxiliary fire alarm boxes, the door of the latter being removed, and only a part of the mechanism of the street box being shown.

A is a street signal box; B an auxiliary street box.

C is a fire alarm circuit; and D is an auxiliary circuit.

In the street box 1 indicates a circuit making and breaking or circuit changing wheel, on which bears a spring 2, on the insulating block 3, the spring being connected to wire 4 and the wheel being connected to wire 5.

6 is a weight suitably connected to the clock-work mechanism for rotating wheel 1 in the ordinary manner. Below the weight is a pivoted arm 7, under which is a spring 8, tending to raise said arm, and also a contact spring 9, connected to wire 10; arm 7 is connected to wire 11 through spring 8.

I prefer to support the auxiliary street box directly above the described street boxes, for example, by means of a screw-threaded connection 12, through which wires may pass—but this is not essential.

Within the auxiliary box is a circuit mak-

ing and breaking or changing signal wheel 13, driven by a suitable clock-work motor, in the usual manner, and having preferably the same number and arrangement of teeth as the circuit wheel in the street box; but the propelling motor or clock-work is, or may be, so regulated that makes and breaks will either be a little slower or a little more rapid than those of the street box, so that the attendant at the fire alarm station will know whether a street box or an auxiliary box is sending in an alarm.

On the periphery of the circuit wheel 13 bears a contact spring 14, connected by wire 15 to one wire of the fire alarm circuit C.

16 is a magnet, one terminal of which is connected to the auxiliary circuit by wire 17, and the other terminal of which is connected by wire 18 to the circuit breaker 19, thence by wire 20 to wire 11. The armature lever 21 of this magnet is pivoted at 22, and has an adjustable screw or stop 23 for the regulating fan or suitable escapement 24 of the clock-work or motor.

At the end of the armature lever is a hook 25, which normally rests behind the beveled head 26 of the lever 27, pivoted at 28, and having a spring 29 tending to move the upper end of the lever toward the left. The upper portion of the lever 27 is insulated from the lower portion as indicated at 30. At the lower end of the lever 27, is a contact spring 31, which normally stands near to but out of contact with a wheel 32, which is driven by the same motor that drives the circuit wheel 13, and which has at one point in its periphery a notch 33. The spring 31 is connected to wire 5, as shown.

I have not herein shown any particular arrangement of the auxiliary circuit outside of the signal boxes. This circuit may have auxiliary sending boxes with circuit closers and return calls, as shown in my patent above referred to, or it may have other devices for accomplishing the same object, as in my well-known multiple arc auxiliary system. The circuit may also be provided with suitable testing devices. Suppose current to be sent over the auxiliary circuit by operation of any suitable circuit controller or "sending box;" the actuating magnet 16 is thereby energized, pulling down its armature, releasing the fly

24, starting the circuit wheel 13, and releasing lever 27, allowing it to move toward the left, bringing spring 31 against the wheel 32, but not disconnecting springs 19. This closes a short circuit around the contact spring 2 and circuit wheel of the main or street signal box, as follows: from wire 5 to spring 31, to wheel 32, to the frame of the clock-work, to wire 4. It is evident, therefore, that if the 10 street box is operated by hand after the auxiliary box has been released by the auxiliary circuit the street box will have no effect on the fire alarm circuit because of said short circuit. Interference is therefore prevented. As 15 the arm 27 moves toward the left the circuit through wires 18 and 20 will be interrupted. This is for the purpose of operating a return call (not shown) in the auxiliary circuit. When the circuit wheel 13 has made the required 20 number of turns the notch 33 comes under spring 31, allowing lever 27 to move far enough to disconnect springs 19, coming to rest against stop 8 and spring 31, remaining out of contact with the wheel 32, thus 25 opening the shunt around the street box. The breaking of the auxiliary circuit at 19 sends a return call, as in my patent referred to, and the armature lever 21 is returned to its normal position by its retracting spring, 30 and this movement returns lever 27 by means of the cam head 26 and hook 25, thereby leaving the apparatus in condition to use again.

If the street box had been pulled first, so that it was sending in an alarm when the 35 auxiliary circuit was closed at a sending box, to operate the auxiliary box, said auxiliary box could not be operated because the auxiliary circuit would be open between the lever 7 and the spring 9, since the street box is operated by raising weight 6, and then allowing 40 it to descend in the well known manner.

It will be noticed that one of the signal 45 boxes is rendered inoperative, when the other is operated, by being short-circuited, and that the other box is rendered inoperative, when the first mentioned box is operated, by having its circuit opened, but I do not limit myself to the particular means for rendering one box inoperative when the other box is operated; and it is evident that the particular 50 construction of the street boxes and of the auxiliary boxes is immaterial so long as they are adapted to operate in substantially the manner above described. The auxiliary box 55 may send a different signal from its street box, but it should be such that the fire department will understand that it designates the same fire district.

By employing the auxiliary signal box, 60 sending a signal corresponding to the street box, I am able to send the same signal by means of the auxiliary circuit and box as would be sent by the street box, and the aux-

iliary system is made independent of the fire 65 alarm system, so far as admission to the fire alarm street boxes by persons in charge of the auxiliary system is concerned, after the system is once installed, and this is a great advantage, for many reasons.

I claim—

1. The combination with a fire alarm or similar signal mechanism and a main circuit therefor, said mechanism having means for changing the fire alarm circuit in a predetermined manner for sending a signal, of 75 an auxiliary signal mechanism also having means for changing the fire alarm circuit to send a signal, means in each mechanism for rendering the other mechanism inoperative, and an auxiliary or releasing circuit for said 80 auxiliary box, substantially as described.

2. The combination of a street box having means for sending a signal over the main circuit, an auxiliary signal box, with means for sending a corresponding signal over the 85 same main circuit, an auxiliary or releasing circuit for the auxiliary box, and means for rendering one box inoperative on said main circuit when the other box is operating, substantially as described.

3. The combination of a street box A having circuit controlling devices for sending a signal, the auxiliary signal box B, having similar circuit changing devices, for sending a signal on the same circuit as the street box, 95 a circuit closer 31, 32 in the auxiliary box for short-circuiting the street box, and a circuit breaker in the street box in the auxiliary circuit, substantially as described.

4. The combination of box A, having suitable signal sending devices, the signal box B, having similar signal sending devices, and main and auxiliary circuits both of which enter both of said boxes, substantially as described.

5. The combination of box A, having suitable signal sending devices, the signal box B, adjacent to box A, and joined to it by a tubular connection 12, and having similar signal sending devices, and main and auxiliary circuits, both of which enter both of said boxes, substantially as described.

6. The combination with a main signal mechanism adapted to send a predetermined signal on a main circuit, of a duplicate signal mechanism having its signal wheel connected on the same main circuit, an auxiliary circuit to actuate said duplicate mechanism from a distance, and means in the duplicate mechanism for sending a return signal only 115 when it has been properly actuated by the auxiliary circuit, substantially as described.

JOSEPH SACHS.
